UNITED STATES PATENT OFFICE.

ISIDOR J. KUSEL, OF CHICAGO, ILLINOIS.

DESIGN FOR A POCKET SAVINGS-BANK.

47,237.

Specification for Design.

Patented Apr. 13, 1915.

Application filed November 5, 1914. Serial No. 870,519. Term of patent 7 years.

To all whom it may concern:

Be it known that I ISIDOR J. KUSEL, a citizen of the United States, residing at 2917 South State street, Chicago, in the county of Cook and State of Illinois, have invented a new, original, and ornamental Design for a Pocket Savings-Bank, of which the following is a specification, reference being had to the accompanying drawing, forming part thereof.

Figure 1 is an edge view of a pocket savings bank embodying my new design; Fig. 2 is a perspective view of the same; Fig. 3 is a plan view of the same.

I claim:

The ornamental design for a pocket savings bank, as shown.

ISIDOR J. KUSEL.
